UNITED STATES PATENT OFFICE.

WILL C. NEAHR, OF DENVER, COLORADO, ASSIGNOR TO THE PROTECTIVE SIGNAL MANUFACTURING COMPANY, OF DENVER, COLORADO, A CORPORATION OF COLORADO.

LAMP SUPPORT.

Application filed February 12, 1920. Serial No. 358,140.

To all whom it may concern:

Be it known that I, WILL C. NEAHR, a citizen of the United States, residing at Denver, in the county of Denver and State of Colorado, have invented certain new and useful Improvements in Lamp Supports, of which the following is a specification.

The present invention relates more particularly to means for supporting electric lamps in their housings or bodies, and is especially useful in connection with automatic signal lamps or railway lamps in which lenses are employed.

The primary object is to provide a simple and compact structure that can be readily introduced into the lamp body and will permit the adjustment of the lamp, so that the lenses will be properly focused thereupon.

A further object is to provide a structure of this type that is a complete unit or article of manufacture, and may be so applied to the lamp body.

The preferred embodiment of the invention is illustrated in the accompanying drawings, wherein:

Figure 1 is a top plan view partly in section of a lamp, showing the support in place therein.

Figure 2 is a view in elevation with half the lamp body broken away.

Figure 3 is a view partly in elevation and partly in section of the lamp support.

Figure 4 is a horizontal sectional view on the line 4—4 of Figure 3.

Figure 5 is a perspective view of the clamping sleeve, and

Figure 6 is a detail horizontal sectional view with the top clamping element removed.

Similar reference numerals designate corresponding parts in all the figures of the drawings.

In the embodiment illustrated, the support comprises a base 7 preferably having opposite flat edges 9 and a flange 10 extending completely around the same. This base is provided with a central circular opening 11 and slots 12 on opposite sides of the same, the said slots being disposed longitudinally of the base and terminating short of the opening 11.

A clamping member in the form of a plate 13 is located beneath the base and extends over the opening 11. This clamping element is provided with an extension 14 hav-

ing an upstanding lug 15 constituting a pivot that is slidable in one of the slots 12 and permits the lateral swinging of the element 13. The element 13 carries a centrally disposed upstanding post or sleeve 16 that extends through the opening 11 and is of less diameter than the same, as will be evidenced by reference to Figure 6.

The sleeve is longitudinally slotted, as shown at 17, and is preferably tapered, the upper portion thereof being externally threaded, as shown at 18. Another clamping element in the form of a plate 19 of greater diameter than the opening 11, is slidable upon the sleeve 16, and rests upon the base 7. A nut 20 is threaded upon the upper end of the sleeve 16 and bears upon the plate 19. The bore of said nut is tapered, and thus serves to contract the upper end of the sleeve when it is screwed down thereupon.

Slidably mounted in the sleeve is a standard or post 21 carrying at its upper end a socket member consisting of a base 22 of insulating material fixed to said post and a contractile shell 23 having ears 24 that can be contracted by a connecting screw 25. The shell preferably is made of sheet metal, and has inclined portions inset, as shown at 26, constituting threads to receive the threads of the usual plug 27 carried by an incandescent lamp 28. The base 22 is provided with a pair of binding posts 29 and 30, the binding post 29 being grounded on the shell 23, and the binding post 30 being electrically connected to a contact spring 31 within the shell 23 and adapted to engage the usual central contact projection of the lamp 28.

The above support is primarily intended to be introduced into a lamp housing or body. Such a body is shown at 32, and is provided with the usual lens 33 mounted in one side. A suitable door 34 is provided at the opposite side. The bottom 35 is provided with a guideway 36 into which the base is adapted to slide. A bowed leaf spring 37, secured on one side of the base 7, serves to hold said base snugly in the guideway 36. With this construction, it will be evident that when the base is in position, the lamp can be easily adjusted, so that it will be properly disposed with respect to the lens 33. By loosening the nut 20, the post 21 can be raised or lowered in the sleeve 16, and said sleeve can be moved toward or from

the lens or laterally with respect thereto. Having obtained the desired position, all that is necessary is to screw down the nut 20, which serves to draw the two clamping elements 13 and 19 into binding engagement with the base 7 and also contracts the sleeve 16 upon the post 21.

From the foregoing, it is thought that the construction, operation and many advantages of the herein described invention will be apparent to those skilled in the art, without further description, and it will be understood that various changes in the size, shape, proportion and minor details of construction, may be resorted to, without departing from the spirit or sacrificing any of the advantages of the invention.

Having thus fully described my invention, what I claim as new, and desire to secure by Letters Patent, is:

1. An adjustable lamp support comprising a base having an opening and a slot at one side of the opening, a lamp-carrying member, and means for clamping the member in different positions on the base, comprising elements on opposite sides of said base, one of said elements extending over the opening and having a pivot slideable in the slot, said element carrying the lamp-carrying member.
2. An adjustable lamp support comprising a base having a central opening and a slot at one side of the opening, a lamp-carrying standard of less diameter than the opening and movable laterally theran, a clamping element beneath the base engaged with the standard and having a pivot slideable in the slot, a clamping element on the base movable with the standard, and means for drawing the elements together against the base.
3. An adjustable lamp support comprising a base, a clamp movable on the base and including a contractile sleeve, a lamp-carrying standard engaged in the sleeve, and common means for contracting the sleeve on the standard and causing the clamp to be tightened to hold it against movement.

4. An adjustable lamp support comprising a base, a clamp movable on the base and including a contractile sleeve, a lamp-carrying standard engaged in the sleeve, and a nut threaded on the sleeve for contracting it about the standard, said nut also acting on the clamp to tighten it on the base.

5. An adjustable lamp support comprising a base, a clamp movable on the base and comprising gripping elements on opposite sides of the base, and a contractile sleeve connecting the elements, a lamp-carrying standard slideable in the sleeve, and means on the sleeve for contracting it and for drawing the gripping elements towards each other.

6. An adjustable lamp support comprising a base having an opening and a slot alongside the opening, a clamping element on the underside of the base having a pivot slideably engaged in the slot, a clamping element on the upper side of the base, a contractile sleeve connecting the elements and passing through the opening, a clamp carrying standard slideable in the sleeve, and a nut for contracting the sleeve threaded thereon and constituting means for causing the elements to grip the base.

In testimony whereof, I affix my signature in the presence of two witnesses,

WILL C. NEAHR.

Witnesses:

A. E. BACON,
ETHEL GARNER.
